SWITCH

James F. Beal, Bridgeport, Conn., assignor to
 Bryant Electric Company, Bridgeport, Conn., a
 corporation of Connecticut

Application January 28, 1942, Serial No. 428,483

8 Claims. (Cl. 200—5)

This invention relates generally to switches for controlling electric circuits, and more particularly to such switches which are capable of controlling a plurality of circuits in a predetermined sequential manner.

For certain apparatus having starting and running circuits, it is necessary that both circuits be closed to energize the apparatus, and after a short time, it is desired that the starting circuit be opened especially where this circuit is useful only at the time the apparatus is initially energized. An example of such apparatus is a fluorescent lamp unit provided with filaments adapted to be connected in series circuit relation in starting the unit, after which line potential is applied across the filaments in the running circuit of the unit. For such apparatus, it is highly desirable that the circuits be under the control of a single switch unit preferably having a single operating member so that the desired sequence of switching operations may be carried out in a relatively simple manner.

Accordingly, one object of this invention is to provide a novel switch unit of the type described having a single operating member for actuating a plurality of switches in a predetermined sequential manner.

Another object of this invention is to provide a novel switch unit of the type described which is compact in form and relatively simple in operation.

Another object of this invention is to provide a switch unit of the type described, novel operating means for actuating a plurality of sets of switch contacts in a predetermined sequential manner.

Another object of this invention is to provide a novel switch unit of the type described adapted for the control of a plurality of fluorescent lamp units from a single source of supply.

Still another object of this invention is to provide novel operating means for at least one set of switch contacts.

These and other objects of this invention will become more apparent upon consideration of the following detailed description of a preferred embodiment thereof and upon consideration of the attached drawing, in which:

Figure 1 is a side elevational view of a switch constructed in accordance with this invention.

Fig. 2 is an elevation view partially in section of the switch shown in Fig. 1 with one casing section removed.

Fig. 3 is a sectional view of the casing taken substantially on the line III—III of Fig. 2, with

certain of the parts within the casing shown in elevation, and

Fig. 4 is a diagrammatic view illustrating how the switch of this invention may be used for the control of a plurality of fluorescent lamp units.

This invention, as stated above, is concerned with the provision of a relatively simplified form of manually operable control device for fluorescent lamp units. Accordingly, for a better understanding of the invention, a detailed description of the switch unit will be given first, after which reference will be had to the manner in which such a unit may control one or more fluorescent lamp units.

The switch unit illustrated is preferably housed in a casing 2 of insulating material preferably a molded insulating material, and the casing 2 is formed of a pair of substantially identical half sections 4 and 6 removably secured together, for example, as by screws 5. Each casing section is hollowed out in a particular manner, so as to form, when the sections are secured together, an inner chamber for the switch elements. Referring to Fig. 2 of the drawing, it can be seen that casing section 6 is provided at the upper end of the hollow portion thereof with a pair of resilient contact strips 8, 10, which may be of any desired resilient conducting material, such, for example, as brass or other copper alloy. Each resilient contact strip 8 and 10 is substantially U-shaped in form, and is provided with a relatively short leg 12 adapted to be seated in a cavity formed in the upper end wall of casing section 6, and the free end of leg 12 is laterally deflected 20 towards the other leg of the strip as at 14, so as to engage the laterally extending end of the cavity in which leg 12 is located. The bight portion of each contact strip is provided with an indentation 16 for receiving a projection on the other end wall of the cavity receiving leg 12 of the contact strip. The other leg 18 of U-shaped contact strips 8 and 10 is longer than leg 12, and when the parts are assembled in position in their respective cavities in casing section 6, the ends 25 of the long legs will be disposed in overlapping relation as shown in Fig. 2. Contact strips 8 and 10 are identical in form and may be assembled in casing section 6 facing each other by merely dropping the sections laterally into the cavities provided therefor. Where it is desired to control a pair of fluorescent lamp units, casing section 4 may also be provided with a set of contact strips 8 and 10 in a manner identical with that shown in Fig. 2 for casing section 6.

For the purpose of causing engagement and

disengagement of the long legs 18 of U-shaped contact strips 8 and 10, a cam member 20 is rotatably mounted between the casing sections, for example, as by a pivot pin 22 projecting from opposite ends of the cam to be rotatably received in circular recesses formed in the casing sections 4 and 6, respectively. Operating cam 20 is provided with spaced operating projections 24 and 26 disposed in opposition to contact strips 10 and 8, respectively, and the cam is further provided with an actuating projection 28 located substantially opposite operating projections 24 and 26.

Contact strips 8 and 10 are operated into and out of engagement with each other by oscillation of cam 20 about its pivot shaft 22. Thus, in the position shown in Fig. 2, projection 26 is in engagement with contact strip 8 to maintain it away from the contact strip 10. Now upon rotation of cam 20 in a clockwise direction from the position shown in Fig. 2, projection 26 will be moved away from contact strip 8 and projection 24 will be moved into engagement with contact strip 10 to urge it upwardly into engagement with contact strip 8 and thereby close the circuit through these contacts. It will be noted that although contact strips 8 and 10 are readily assembled by merely dropping them laterally into the cavities formed in the housing sections, that when they are assembled in the position shown in Fig. 2, they are effectively anchored against movement under the force exerted by engagement of operating cam 20 therewith. Thus indentation 16 on the contact strips prevents movement of the strips downwardly, as shown in Fig. 2, and also prevents rotation of these strips by the force exerted on the long legs thereof by cam projections 24 and 26, respectively. As previously stated, the contact strips 8 and 10 are preferably of a resilient conducting material, and are preferably formed so that the overlapping ends thereof will normally assume a position in which they are in engagement. Thus in the position shown in Fig. 2 the long leg of contact strip 8 has been stressed by cam 20 in moving it from engagement with contact strip 10. Accordingly, when cam 20 is rotated in a clockwise manner, contact strip 8 will return into engagement with contact 10, and such engagement will be insured by the engagement of cam projection 24 with strip 10.

In the lower portion of casing section 6, there are provided substantially S-shaped contact strips 30 formed preferably of a resilient conducting material like contact strips 8 and 10. S-shaped contacts 30 are preferably located, as shown in Fig. 2, in the lower corners of casing section 6, and one end leg 32 of each contact strip 30 is mounted in a cavity formed in the lower corners of casing section 6. Each of these cavities is formed with a projection 34 overlapping the free end of leg 32 to thereby prevent rotation of the contact strip in a clockwise direction. Contact means for bridging S-shaped contact strips 30 is carried on a rotatable support 36 of insulating material, such, for example, as a molded insulating material. Rotatable support 36 is provided with a ratchet-like tooth configuration about the periphery thereof, and the other end leg 32 of S-shaped contact strips 30 is preferably formed for close engagement with the space between the teeth-like formations on rotatable support 36. The bridging contact proper is formed by a plate 40 of conducting material such, for example, as copper or the like, secured at one face of rotatable support 36, and having laterally ex-

tending contact arms 42 extending over alternate faces of the teeth formed on the periphery of rotatable support 36.

It will be apparent that the switch construction mounted in the lower portion of casing section 6 is operable by rotation of insulating support 36. The insulating support 36 is preferably rotatably mounted by means of a shaft 37 affixed thereto and extended from opposite sides thereof to find bearing support in circular cavities formed in the respective casing sections. Upon rotation of support 36 in a counterclockwise direction, legs 38 of resilient contact strips 30 will snap over the outer ends of the teeth formed on the support and successively engage the curved surfaces between successive teeth at successive positions. Accordingly, at alternate positions of member 36, it will be apparent that conducting plate 40 through arms 42 thereof will act to conductively bridge the contact strips 30 to complete the circuit through this switch.

For the purpose of rotating insulating support 36, there may be formed integral therewith, a ratchet wheel 44 having teeth thereon corresponding in number and position to the tooth-like formation on the periphery of rotatable support 36. For the purpose of opening and closing the circuits controlled by contact strips 8, 10 and contact strips 30 in a predetermined sequential relation, there is provided a single operating means for rotatable support 36 and cam 20. This operating means includes a substantially U-shaped operating member preferably formed of strip resilient material, having a relatively long leg 48 notched at one side as at 50 for receiving operating projection 28 of cam 20, and having a relatively short leg, the free end of which is bent to form a hook portion 54 for cooperation with ratchet 44. The bight end of the U-shaped actuating member 46 is adapted to be slidably received in a cavity 52 formed in one inner side wall of casing 2.

Each casing section 4, 6 is provided at the side opposite cavity 52 with a semi-circular opening which is grooved for receiving the flange 56 formed on a mounting sleeve 58 adapted to project from the casing. Mounting sleeve 58 is adapted to be assembled with the casing sections before they are secured together, so that after securing screws 5 are in place, flange 56 prevents relative movement of the mounting sleeve and casing. As shown, the outer surface of mounting sleeve 58 is preferably threaded so that the switch may be supported from a single mounting aperture, by extending mounting sleeve 58 through the aperture and drawing a nut up on the sleeve. The outer end of mounting sleeve 58 is provided with an inwardly extending short flange 60 for limiting outward movement of an operating handle member 62 by engagement of an outwardly extending flange 64 on the handle. A flanged collar 66 is preferably mounted within mounting sleeve 58 and normally engages a ledge formed on the casing sections, to prevent movement of the flanged collar into the casing. An operating member 68 is slidably mounted in flanged collar 66, and the outer end of operating member 68 is provided with an outwardly extending flange 70, and a coil compression spring 72 is adapted to react between flange 70 on operating member 68 and flanged collar 66 to bias operating member 68 outwardly and maintain operating handle 62 in its normal position shown in Fig. 2. Leg 48 of U-shaped operating member 46 has the free end thereof secured to the inner end of slideable operating member 68, as at 74 by soldering, riveting or the like,

It will now be apparent that the switches may be operated by manually angularly deflecting operating handle 62, or by a direct inward movement thereof, to cause sliding movement of operating member 68 inwardly of the casing, and consequent movement of U-shaped actuating member 46 in the same direction. This will cause rotation of cam 20 in a clockwise direction about its pivot 22 to cause engagement of contact strips 8 and 10. Hook portion 54, of actuating member 46 will engage a tooth of ratchet 44 to cause rotation of insulating support 36 in a counterclockwise direction, the distance of one tooth, to thereby bring conducting flanges 42 of the bridging contact into engagement with contact strips 30, respectively, and complete the circuit between these contacts. Now upon release of operating handle 26, spring 72 will cause movement of operating member 68 and U-shaped operating member 46 outwardly relatively to casing 2, and cause the operating handle to resume its normal position shown in Fig. 2. This outward movement of the parts will cause cam 20 to rotate in a counterclockwise direction back to the position shown in Fig. 2, and thereby separate contact strips 8 and 10. This outward movement of the switch operating parts, will have no effect on the bridging contact for contact strips 30, and consequently the circuit through these contacts will remain closed. In order to open the circuit through contact strips 30, it will be necessary to again angularly deflect or inwardly slide operating handle 62 to cause rotation of ratchet 44 by pawl hook 54 to bring conducting flanges 42 on insulating member 36 out of engagement with contact strips 30. Of course, such an actuation of handle 62 will also cause engagement of contact strips 8 and 10 upon inward movement of the parts, and disengagement thereof upon outward movement of the parts, as before. Accordingly, it can be seen that contact strips 8 and 10 are moved into engagement upon sliding movement of operating member 46 inwardly of the casing and out of engagement upon movement of this member outwardly relative to the casing, whereas the circuit is completed or interrupted between contact strips 30 only upon movement of operating member 46 inwardly relative to the casing, and movement of operating member 46 outwardly relative to the casing has no effect on the bridging contact for contact strips 30.

Each of the contact strips 8, 10 and 30 preferably has an aperture through the leg portion thereof seated in a casing cavity, and the casing sections are provided with grooves for electrical conductors entering the casing so that the ends of the conductors when stripped may be inserted through the apertures in the adjacent legs of the contact strips and bent and soldered or otherwise secured to the respective strips. Thus it can be seen from the drawing that a conductor 78 is secured to contact strip 10 associated with casing section 6, and a conductor 78 is secured to contact strip 8 associated with casing section 6, whereas conductors 80 and 82 are connected respectively to contact strips 8 and 10 associated with casing section 4. Similarly, conductors 84 and 86 are connected to contact strips 30, respectively.

As previously stated, this switch is intended for use especially with apparatus such as fluorescent lamp units having a starting circuit and a running circuit. There is accordingly, shown in Fig. 4, an illustration of how a switch constructed in accordance with this invention may be used to control energization of a pair of seri-

ally arranged fluorescent lamp units 88. In accordance with Fig. 4, contact strips 8 and 10 have their conductors 80 and 82 connected in series with the filaments of one lamp unit, and the other set of contact strips 8, 10 is connected in series with the filaments of the other lamp unit. One filament of one unit is connected by conductor 86 to one contact 30, and the other contact 30 may be connected to a supply conductor 84. The other filament of this lamp and one filament of the other lamp are serially connected by a conductor 90, and the other filament of the other lamp is connected to the other supply conductor 92. Suitable ballast means 94, such as an incandescent lamp or the like, may be included in conductor 92. It will be noted that each set of contacts 8, 10, has a condenser 96 in shunt relation therewith for the purpose of eliminating radio interference, and conductors 88 are provided for establishing the connections of these shunt circuits. The condensers 96 are preferably supported directly on and as a part of this switch unit, in depressions formed on the outer side wall of each casing section 4, 6. The condensers are maintained in the depressions formed on the outside of each casing section by cover plates 100 held in place by screws 5, which also act to maintain the casing sections assembled, and conductors 88 are adapted to extend through an aperture 98 formed in each casing section for connection to their respective contacts 8, 10.

In the circuit arrangement illustrated in Fig. 4, it will be observed that when the circuit is completed through contacts 30 and both sets of contacts 8, 10, that the filaments of both lamps will be in a series circuit between supply conductors 84 and 92. This corresponds to the condition of these contacts when operating switch handle 62 is angularly moved from the position shown in Fig. 2. Now upon release of the operating handle, contacts 8 and 10 will be separated, to open the series circuits through the lamp filaments, but the serial arrangement of the lamps will be undisturbed. The particular switch structure disclosed is equally adapted for use with a parallel connection of lamps, because in such an arrangement contact strips 8 and 10 are connected to the lamps in the same manner shown in Fig. 4, but conductor 90 is eliminated, and conductor 86 would be connected to one filament of each lamp and supply conductor 92 would be connected to the other filament of each lamp.

From the foregoing, it is believed readily apparent that this invention provides a relatively simplified switch construction embodying a plurality of switches mounted in a single casing of insulating material, and having a single reciprocable operating member to open and close one set of switches on one complete reciprocation thereof, and to open or close another switch on a complete reciprocation thereof. This single operating means common to all the switches is adapted for manual operation to cause movement in one direction, and resilient means are provided for return movement in the opposite direction. Furthermore, the switch unit disclosed may be adapted by the provision of two starting switches for operation of a pair of devices such as fluorescent lamp units in either a series or parallel arrangement. Obviously, while but two sets of contact strips 8 and 10 are shown in the embodiment illustrated, it is obvious that a greater number, or but a single set of contacts, could be employed to control a like number of lamp units arranged in either a serial or parallel ar-

angement. The novel switch unit disclosed also contemplates the provision of condensers connected across the starting contacts and forming a part of and being carried by the switch unit. Because of the compact arrangement of the several sets of contacts and the condensers, the unit may be made small in size, and this is an especially important feature where lamp units are mounted on their own bases such as in desk lamps or floor or table lamps for household use. In such applications, space considerations are very stringent and the controls for the lamp units may be required to conform to very small space requirements. In this connection it should be noted that the switch may be mounted in a single mounting aperture by virtue of mounting sleeve 58, and that although a tiltable actuating handle 62 is disclosed for actuating the switches of the unit, other actuating means such, for example, as a pull chain or the like, may be provided to actuate handle 62 where operation is desired from a remote point. All of the switches are enclosed as a single unit in a casing of insulating material, so that no live parts are exposed, to thereby form a safe control unit, as well as one which is of a simplified and compact form.

Having described a preferred embodiment of the invention in accordance with the patent statutes, it is desired that the invention be not limited to the particular embodiment disclosed, inasmuch as it will be obvious particularly to persons skilled in the art that many changes and modifications may be made in this particular embodiment without departing from the broad spirit and scope of this invention. Accordingly, it is desired that the invention be interpreted as broadly as possible, and that it be limited only as required by the prior art.

I claim as my invention:

1. In a switch, a switch casing of insulating material, spaced resilient contacts mounted in said casing, spindle means rotatably mounted in said casing, said spindle means having spaced peripheral portions of conducting material connected together, and said contacts positioned so as to simultaneously engage a pair of said peripheral portions in at least one position of said spindle means, ratchet means on said spindle means, a pawl member reciprocably mounted in said casing and engageable with said ratchet means for rotating said spindle means an amount equal to the distance between successive peripheral portions of said spindle means upon each complete reciprocation thereof, said pawl member comprising a substantially U-shaped member having the bight portion thereof slidably supported in a socket formed on one wall of said casing, actuating means for said pawl member movably mounted in an aperture through an opposite wall of said casing, one leg of said pawl member being extended for connection to said actuating means, and the other leg of said pawl member having a pawl hook formed thereon for cooperation with said ratchet means.

2. In a switch, a switch casing of insulating material, spaced resilient contacts mounted in said casing, spindle means of insulating material rotatably mounted in said casing, said spindle means having spaced peripheral portions of conducting material connected together, and said contacts positioned so as to simultaneously engage a pair of said peripheral portions in at least one position of said spindle means, ratchet means on said spindle means, a pawl member reciprocably mounted in said casing and engageable

with said ratchet means for rotating said spindle means an amount equal to the distance between successive peripheral portions of said spindle means upon each complete reciprocation thereof, said pawl member comprising a substantially U-shaped member having one leg thereof connected with pawl actuating means, and the other leg of said pawl member having a pawl hook formed thereon for cooperation with said ratchet means, a pair of separable contacts in said casing, and means associated with said one leg of said pawl member for opening and closing said separable contacts in response to movement of said pawl in opposite directions.

3. In a switch, a switch casing of insulating material, spaced resilient contacts mounted in said casing, spindle means rotatably mounted in said casing, said spindle means having spaced peripheral portions of conducting material connected together, and said contacts positioned so as to simultaneously engage a pair of said peripheral portions in at least one position of said spindle means, ratchet means on said spindle means, a pawl member reciprocably mounted in said casing and engageable with said ratchet means for rotating said spindle means an amount equal to the distance between successive peripheral portions of said spindle means upon each complete reciprocation thereof, said pawl member comprising a substantially U-shaped member having one leg thereof cooperating with pawl actuating means, and the other leg of said pawl member having a pawl hook formed thereon for cooperation with said ratchet means, a pair of separable contacts in said casing, cam means oscillatably mounted in said casing for opening and closing said separable contacts upon movement of said cam means in opposite directions, and a coupling between said cam means and said one leg of said pawl member to produce oscillation of said cam means in response to reciprocation of said pawl means.

4. In a switch, separable contacts including overlapping strips of flexible and resilient conducting material, actuating means for said contacts comprising a rockably mounted member having spaced portions engageable, respectively, with said strips upon rocking movement thereof in opposite directions to cause engagement and disengagement of said strips.

5. In a switch, separable contacts including overlapping strips of flexible and resilient conducting material, actuating means for said contacts comprising a rockably mounted member having spaced projecting portions engageable, respectively, with said strips upon rocking movement thereof in opposite directions to cause engagement and disengagement of said strips.

6. In a switch, a base, spaced resilient contacts mounted on said base, spindle means rotatably mounted on said base, said spindle means having spaced peripheral portions of conducting material connected together, and said contacts positioned so as to simultaneously engage a pair of said peripheral portions in at least one position of said spindle means, ratchet means on said spindle means, a pawl member reciprocably mounted on said base and engageable with said ratchet means for rotating said spindle means an amount equal to the distance between successive peripheral portions of said spindle means upon each complete reciprocation thereof, said pawl member comprising a substantially U-shaped member having one leg thereof connected with pawl actuating means, and the other leg

of said pawl member having a pawl hook formed thereon for cooperation with said ratchet means.

7. In a switch, a base, spaced resilient contacts mounted on said base, spindle means rotatably mounted on said base, said spindle means having spaced peripheral portions of conducting material connected together, and said contacts positioned so as to simultaneously engage a pair of said peripheral portions in at least one position of said spindle means, ratchet means on said spindle means, a pawl member reciprocably mounted on said base and engageable with said ratchet means for rotating said spindle means an amount equal to the distance between successive peripheral portions of said spindle means upon each complete reciprocation thereof, said pawl member comprising a substantially U-shaped member having the bight portion thereof slidably supported in a socket formed on said base, actuating means for said pawl member movably mounted on said base, one leg of said pawl member being extended for connection to said actuating means, and the other leg of said pawl member having a pawl hook formed thereon for cooperation with said ratchet means.

8. In a switch, a switch casing of insulating

material, spaced resilient contacts mounted in said casing, spindle means rotatably mounted in said casing, said spindle means having spaced peripheral portions of conducting material connected together, and said contacts positioned so as to simultaneously engage a pair of said peripheral portions in at least one position of said spindle means, actuating means for rotating said spindle in one direction, each of said contacts comprising a strip of resilient conducting material substantially S-shape in form and including spaced end legs connected by an intermediate leg, one of said end legs of each contact extending in the direction of rotation of said spindle and positioned to engage the periphery of said spindle means, and spaced, elongated hollow chamber portions provided in the wall of said casing, a limited opening for each of said chamber portions to the interior of said casing and spaced from the end of said chamber portions in the direction of motion of said spindle means, for receiving the other end leg of each contact to support the contacts in operative positions.
